UNITED STATES PATENT OFFICE.

GEORGE P. BARTHOLOMEW, OF ESSEX FELLS, NEW JERSEY, ASSIGNEE TO AMERICAN ABRASIVE METALS CO., A CORPORATION OF NEW YORK.

WEAR-RESISTING STRUCTURE.

1,330,973.

Specification of Letters Patent. Patented Feb. 17, 1920.

Application filed January 13, 1919. Serial No. 270,984.

To all whom it may concern:

Be it known that I, GEORGE P. BARTHOLOMEW, a citizen of the United States of America, residing at Essex Fells, Essex county, State of New Jersey, have invented certain new and useful Improvements in Wear-Resisting Structures, of which the following is a specification.

My invention relates to the production of wear resisting surfaces for stair treads, floors, car steps and platforms, automobile pedals, shoe soles, horse shoe pads and the like, and comprises an improved type of structure for such uses. It has been heretofore proposed to produce structures of this kind by embedding a granulated or powdered mass of some intensely hard and refractory mineral such as alundum or corundum in a matrix of more easily fusible metal, such as cast iron, to form slabs, strips and panels having a wear resisting surface consisting substantially of the granulated or powdered material referred to, but owing to the weight of the casting and the thickness necessary to make articles by this process, it has been found unsuitable for many uses. Moreover such prior structures are very rigid and cannot be made to conform at all to any variations in the contour of the supporting surface.

Broadly stated, my present invention comprises an idea of means for overcoming these and other difficulties inherent in the old structure by providing as a matrix and backing for the granulated alundum or similar refractory material a substance which during or before its final treatment at comparatively low temperatures can be caused to adhere to supporting surfaces (such as a vulcanizable rubber compound). My invention produces a light and somewhat flexible article and has other advantages evident to those skilled in the art and some of which are hereinafter set out with more or less particularity. The best embodiment of certain forms of my invention at present known to me are illustrated in the accompanying sheet of drawings in which:

Figure 1 is a cross section of a wear resisting stair tread applied directly to the supporting staircase or tread.

Fig. 2 is a cross section of a panel em-

bodying my invention provided with a flexible backing or base, and

Fig. 3 shows a cross section of a special form of stair tread.

Throughout the drawings like reference characters indicate like parts: 1, represents a composition formed by mixing a quantity of granulated and finely divided alundum, or similar hard material, with a quantity of rubber and the proper proportion of sulfur or other vulcanizing constituent, which composition is deposited in a layer, before vulcanization, upon the stair tread 2. Care should be taken that the greatest proportion of the alundum should be at or nearest the upper or wearing surface, and the least proportion thereof at the under, or adhering, surface as indicated in the drawing. Conversely the greatest proportion of the rubber compound is at and near the lower surface where its adhesive properties during vulcanization may be directly exerted on the supporting base, and the least proportion in and near the upper surface, there being just enough to hold the alundum particles. This can be accomplished by making the original mixture of a certain conveniently workable proportion of alundum; and then, after the layer has been formed, sprinkling an additional quantity of alundum particles in excess on the surface of such layer and rolling or pressing them in as far as they will go. Also a surface of coarser particles may be added in this latter step, the original mixture comprising finer particles, or the desired localizing of the coarser particles at the wearing surfaces, while any excess of the vulcanizable constituents remains at the attaching surface, may be secured by other means. In any event the object to be attained is the formation of a layer in which the exposed surface shall be a practically continuous body of the alundum or other wear resisting material, while the opposite surface next to the supporting structure has enough rubber in its composition to cause it to firmly adhere thereto during the vulcanizing process.

When the constituent elements are arranged as above described, and illustrated in the drawing, the whole structure (the stair tread and the superimposed layer) may be

subjected to the action of any suitable vulcanizing apparatus. The result is an integral structure all the elements of which are closely knit together, which has a surface highly resistant to wear and which is at the same time slightly resilient, sound absorbent and non resonant.

Another of various possible methods of attaching to a proper support the strip or panel constituting my invention is illustrated in Fig. 2, where 3, is a strip of canvas or other strong, flexible more or less porous or perforated substance onto which the matrix, with its contained alundum 15 constituting the layer 1, has been vulcanized. The under surface of the entire structure so produced is susceptible to the action of ordinary cements and the projecting edges of the backing strip 3, may be easily 20 nailed or clamped to the supporting base. The form shown in Fig. 1 may be most convenient for some forms of stair treads, car steps, automobile pedals, horse shoes and similar structures when the vulcanizing can 25 be done directly to the supporting body, while that in Fig. 2 could more easily be employed for flooring, tiling, soles and heels for shoes, horse shoe pads and in other cases where the supporting structure can 30 not for any reason be present during the vulcanizing step. Thus the form shown in Fig. 2 could be nailed to a wooden stairway or floor, through the projecting portions of the back 3, if it was not desired to perforate 35 the material 1.

In addition to the advantages of my invention previously recited herein it may be observed that an important point is the low temperature at which the original layer of 40 loose material may be transformed into the final panel, strip or other ultimate self-maintaining shape, as this permits the wear

resisting layer to be formed integrally with the supporting structure without said structure being injured or destroyed in the process, even if it be of low heat resisting quality. Thus it is impossible to cast the iron matrix of the prior art structure hereinbefore referred to onto any ordinary supporting structure, and even if possible, it 45 would be a costly and difficult operation, while with my invention nearly any character of supporting material will withstand the temperature of vulcanization without injury, and the rubber and sulfur can be 50 forced into small interstices like the pores of a supporting base, into which molten iron 55 might not penetrate because of the chilling action of the extensive surfaces then exposed.

In the application to stair treads, my invention because of its flexibility and ease of manipulation during the formative process will allow the hard material to be applied to the nosing or outer edge of the 65 tread, which in the case of a down stairway always wears away first and so becomes slippery and dangerous. An example of such a structure is shown in Fig. 3.

Having described my invention, I claim:

As a new article of manufacture a wear 70 resisting panel comprising a self supporting backing and a body of rubber vulcanized thereto, said rubber having granulated mineral masses embedded therein and on its exposed surface, the proportion of mineral matter being greatest at and near the exposed surface and the proportion of rubber being greater near the supporting backing.

GEORGE P. BARTHOLOMEW.
